CLAIM

The ornamental design for a wind collector, as shown and described.

DESCRIPTION

FIG. 1 is a front perspective view of a wind collector;
 FIG. 2 is a front view thereof;
 FIG. 3 is a top plan view thereof;
 FIG. 4 is a right-side view thereof;
 FIG. 5 is a left-side view thereof;
 FIG. 6 is a rear view thereof;
 FIG. 7 is a bottom plan view thereof;
 FIG. 8 is a rear perspective view thereof; and,
 FIG. 9 is a detail view of the portion encircled in FIG. 8.
 The broken lines depict environmental subject matter only
 and form no part of the claimed design.
